(57) **CLAIM**

The ornamental design for a game timer, as shown and
described.

DESCRIPTION

The patent or application file contains at least one drawing
executed in color. Copies of this patent or patent application
publication with color drawing(s) will be provided by the
Office upon request and payment of the necessary fee.

FIG. 1 is an upper front perspective view of a game timer
embodying a first embodiment of my design;

FIG. 2 is an upper rear perspective view of the game timer
shown in FIG. 1;

FIG. 3 is a front elevation view of the game timer shown in
FIGS. 1 and 2;

FIG. 4 is a rear elevation view of the game timer shown in
FIGS. 1-3;

FIG. 5 is a side elevation view of the game timer shown in
FIGS. 1-4, with the opposite side elevation being a mirror
image thereof;

FIG. 6 is a top plan view of the game timer shown in FIGS.
1-5;

FIG. 7 is a bottom plan view of the game timer shown in
FIGS. 1-6;

FIG. 8 is an upper front perspective view of a game timer
embodying a second embodiment of my design;

FIG. 9 is an upper rear perspective view of the game timer
shown in FIG. 8;

FIG. 10 is a front elevation view of the game timer shown
in FIGS. 8 and 9;

FIG. 11 is a rear elevation view of the game timer shown in
FIGS. 8-10;

FIG. 12 is a side elevation view of the game timer shown in
FIGS. 8-11, with the opposite side elevation being a mirror
image thereof;

FIG. 13 is a top plan view of the game timer shown in FIGS.
8-12;

FIG. 14 is a bottom plan view of the game timer shown in
FIGS. 8-13;

(Continued)

FIG. 15 is an upper front perspective view of a game timer embodying a third embodiment of my design;
 FIG. 16 is an upper rear perspective view of the game timer shown in FIG. 15;
 FIG. 17 is a front elevation view of the game timer shown in FIGS. 15 and 16;
 FIG. 18 is a rear elevation view of the game timer shown in FIGS. 15-17;
 FIG. 19 is a side elevation view of the game timer shown in FIGS. 15-18, with the opposite side elevation being a mirror image thereof;
 FIG. 20 is a top plan view of the game timer shown in FIGS. 15-19; and,
 FIG. 21 is a bottom plan view of the game timer shown in FIGS. 15-20.
